UNITED STATES PATENT OFFICE.

WALTER B. BOUTWELL, OF LAWRENCE, MASSACHUSETTS.

COLLAPSIBLE CRATE.

SPECIFICATION forming part of Letters Patent No. 721,003, dated February 17, 1903.

Application filed November 6, 1902. Serial No. 130,296. (No model.)

To all whom it may concern:

Be it known that I, WALTER B. BOUTWELL, a citizen of the United States, residing at Lawrence, in the county of Essex and State of 5 Massachusetts, have invented new and useful Improvements in Collapsible Crates, of which the following is a specification.

This invention relates to a collapsible crate particularly adapted for packing and conveying 10 eggs; and the object of the same is to provide a simple and effective device of this class capable of being reduced to compact form for return shipment or storage. The improved crate is of that type of such devices 15 formed of a number of bars or strips having their ends overlapped and pivotally connected by rods or bolts and which are reduced to a knockdown or collapsed condition by removing the top and bottom and pressing the 20 sides together from diagonally opposite points, whereby corresponding parts are folded one upon the other.

The present invention consists in the details of construction and arrangement of the 25 several parts, which will be more fully hereinafter described and claimed.

In the drawings, Figure 1 is a perspective view of a crate embodying the features of the invention. Fig. 2 is a longitudinal vertical 30 section of the same. Fig. 3 is a plan view of the crate shown in knockdown condition or collapsed. Fig. 4 is an edge elevation of the crate as shown by Fig. 3.

Similar numerals of reference are employed 35 to indicate corresponding parts in the several views.

The numeral 1 designates the sides of the improved crate, which are all preferably of equal length and formed of a series of bars 40 or slats 2, having their ends 3 overlapped and pivotally connected by bolt-rods 4, passing vertically downward therethrough. At upper and lower portions of two of the sides holding-strips 5 are terminally overlapped in 45 relation to the bars or strips 2 and also secured by the bolt-rods 4. At intermediate points the bars or strips 2 in all the sides have brace-rods 6 passed therethrough, one at each side, to prevent the bars or strips 2, below 50 the uppermost similar bar or strip on two of the sides and through the bars or strips of the remaining sides between the upper and

lower holding-strips 5, from warping out of shape or becoming bulged outwardly by pressure within the crate.

The improved crate is provided with a removable top and bottom 7 and 8, of duplicate construction, and each comprises a series of strips 9, broader than the bars or strips 2, connected at opposite extremities by right-angularly-disposed stop-strips 10. The outer edges of the strips 10 are at a distance from the terminals of the strips 9, so that the extremities of the top and bottom may engage the holding-strips 5, the said extremities of the top 65 extending under the holding-strip and the extremities of the bottom resting over its holding-strips, as fully shown by Fig. 1. The stop-strips 10 terminate flush with the outer edges of the strips 9 at the outer portions of 70 the top and bottom, and the outer edges of the outer strips of the latter snugly fit against the inner upper portions of the top bars or strips 2 of two of the sides. Extending across the centers of the strips 9 and secured thereto is a combined supporting and fulcrum strip 11, having its ends projected outwardly over the outer edges of the outer strips 9 to bear on the upper edges of the top bars or strips 2, inside of which said outer strips 9 are 80 located. It will be understood that the top 7 will have the strips 11 and 10 on the upper sides thereof and the bottom 8 will have said strips on the lower side thereof, as clearly 85 shown by Fig. 2.

In attaching the top 7 and bottom 8 to the sides of the crate the one end of each of such devices is pushed in between the holding-strip 5 and the adjacent bar or strip 2 by pressing downwardly on one end of such device, and 90 during this operation the combined supporting and fulcrum strip 11 will have its ends bearing on the edges of the bars or strips 2 with which it is adapted to normally engage. The one end of the bottom or top is pushed far 95 enough between the adjacent strip 5 and bar or strip 2 to permit the opposite end of such bottom or top to clear the inner portion of the opposite strip 5 and depress below or above said opposite strip 5, as the case may be, in accordance with the application of the top or bottom. When this position of the bottom or top has been obtained, it is pushed longitudinally or in the direction of the length of 100

the strips 9 until both ends are between the strips 5 and the adjacent bars or strips 2, but in close contact with said strips 5. When the top 7 and bottom 8 are assembled in connection with the crate, as just explained, the latter will be prevented from collapsing and may be shipped or otherwise transported from one place to another. When it is desired to collapse the crate, one end of the top or bottom 10 is pushed inwardly into the crate and moved longitudinally to clear the opposite end, when a complete separation can ensue, and when both the top and bottom are detached the crate may be rested on one corner and pushed 15 downwardly in a diagonal direction to compress the parts into compact form, as shown by Figs. 3 and 4. The top and bottom may then be placed upon and fastened to the collapsed crate-body, and in this condition a 20 number of the crates may be stored in compact form for reshipment or return to the owner, as well as to effect occupancy of a small space when not in use. When the top and bottom are applied to the crate, the stop- 25 strips 10 prevent longitudinal displacement thereof, and the combined supporting and fulcrum strips 11 obstruct inward movement of the top or bottom into the body of the crate.

30 It is proposed to place cells of ordinary form within the crate and separate the same

by the usual partitions, and instead of using the crate for packing and transporting eggs it may be employed for shipping other goods or fruits as well as poultry. The improved 35 crate will be found exceptionally convenient, and changes in the proportions and dimensions may be made at will.

Having thus fully described the invention, what is claimed as new is—

40 A collapsible crate having holding-strips at the upper and lower portions of two sides thereof in spaced relation to members of the said sides, and a removable top and bottom, each having stop-strips adjacent the opposite ends and of a length to permit the said top and bottom to be pressed inwardly into the crate, and immovably-secured fulcrum-strips extending across the centers of the top and bottom and of greater length than the 45 stop-strips, the fulcrum-strips also acting as supports for the top and bottom, whereby the latter may be depressed or pushed inwardly into the crate at either extremity for the purpose of applying and removing the same. 50

55 In testimony whereof I affix my signature in presence of two witnesses.

WALTER B. BOUTWELL.
